CONDUCTOR CABLE

Adriano Cavaliere Ducati, Bologna, Italy, assignor,
by means assignments, to Transducer Corporation,
New York, N. Y., a corporation of New York

Application September 24, 1937, Serial No. 165,432
In Italy October 19, 1936

3 Claims. (Cl. 174—28)

This invention relates to conductor cables and more particularly to cables of the co-axial type, that is to say, in which a plurality of conductors insulated from one another are arranged in the cable about a common axis.

5 Prior to my invention conductor cables of the co-axial type have come into common use and are accepted as an important part of numerous electrical installations. Such cables are in general made with a central conductor and spacers of various varieties and an external annular conductor held in substantially co-axial relation with the central conductor by means of the spacers and finally an outer insulating sheath designed to prevent moisture from entering the cable.

10 It is an object of the invention to provide a cable which will be flexible, of attractive appearance, simple and economical to manufacture and easily used.

15 Another object of the invention is to provide a cable which will be flexible and easy to handle but which will have low capacitance and low surface leakage losses along the surface of the insulators between the conductors of the cable.

20 Another object of the invention is to provide a cable which is so light that it can be treated as a self-supporting unit and its entire weight even carried by the central conductor, if desired.

25 Another object of the invention is to provide a cable capable of exposure to ordinary variations of atmospheric conditions without serious variations in its conducting and di-electric characteristics.

30 With these and other objects in view my invention contemplates the combination of a central conductor with beads of insulating material strung thereon adapted to support the outer conductor in co-axial relation and to shift angularly each on the next so that the cable can be flexed at will and an outer conductor consisting of an 35 open mesh wire braid supported by the sides of the bead.

40 In the accompanying drawing I have shown two preferred embodiments of my invention. These are given with a view to explaining and illustrating the invention and the best manner of embodying it in practical use. These are not, however, intended to be exhaustive nor limiting 45 of the invention, but on the contrary the drawing and the following description are designed to instruct others in the invention so that they will be able to embody it in numerous forms and modifications, each as may be best suited to the requirements of any particular use.

50 In the drawing:

Fig. 1 is a view partly in elevation, partly in axial section of a two conductor cable embodying my invention; and

Fig. 2 is a similar view of a three conductor cable embodying my invention.

5 Referring first to Fig. 1, I have shown therein a central conductor 10, e. g., of stranded wire. On this are strung beads 11, each of which has a domed end with a contact area 12 having spherical surface and a neck 13 projecting beyond the spherical surface in order to lead away from the central conductor any moisture which may enter between the adjacent beads and flow across the spherical surface. This neck and also the spherical surface itself serve to reduce surface leakage losses.

10 Through the ends of the bead 11 and the neck 13 is a central opening substantially conical in shape and having its smaller end approximately fitted to the central conductor 10. The conical shape of this opening is designed to permit the angular movement of the beads as the cable is flexed without producing short bends in the central conductor which might with repeated bending fatigue the metal to a point where a failure 15 would occur. As shown specifically in Fig. 1 of the drawing, the part 13 of the beads which makes contact with the wire is normally in contact therewith along about 10% of its length only. Conceivably, however, if the cable were bent to the minimum radius possible, the beads might 20 make contact with the wire along as much as 25% of its length. This, however, would be an extreme condition, and would be avoidable in practice by never bending the cable to the minimum radius possible.

25 Each of the beads is, as shown, thimble shape, i. e., hollow, and its end opposite to the dome forms an annular edge which engages the spherical surface of the next bead. Thus a continuous 30 circular contact is made with the spherical surface and is maintained even when the beads are moved angularly with respect to one another as 35 the cable is flexed.

40 These beads are made of an insulating material, advantageously one which is non-hygroscopic and has good dielectric properties. I have found that a material which is most advantageous both from the point of view that it is non-hygroscopic, that it withstands exposure to the atmosphere and weathering, and that it has very favorable and constant di-electric properties, is the class of poly styrol plastics, particularly the material manufactured and sold in Europe under 45 the trade mark "Ipertrolitol".

The outer sides of these beads 11 are substantially cylindrical in form, whereby to support the second co-axial conductor, namely, the open mesh wire braid 15. It is important that the form of the beads 11 supports the wire of the sheath without sharp turns and that the wires of the braid are free to shift along the smooth surface of the bead. It is important also, especially where no external moisture proof insulation is used, that the wire braid is of open mesh so that air can circulate through the braid and over the surfaces of the beads so that, should any water collect on the cable, as for example, during a rain, it can be quickly dried and will not be entrapped under the wires.

Due to the form of the beads 12 and to the open mesh character of the braid and to the absence of any heavy external insulation in the example illustrated, the cable is extremely light and it will be found in practically all cases entirely practicable to treat it as a self-supporting unit, or even to support it entirely upon the central conductor.

Another advantage of the open mesh braid freely sliding over the surface of the insulation is illustrated at the right-hand end of Fig. 1, namely, the simplicity with which connector terminals can be applied. In the case illustrated a narrower cylindrical bead of insulation material 16 is slipped over the end of the central conductor 10 and against the first thimble-shaped bead 11. This bead 16 may, as shown in the example, be of a diameter to constitute essentially an extension of the neck 13 of the first bead, or it may even be omitted and the neck 13 used for this purpose. The braid 15 is then stretched axially whereby it is attenuated over the end of the bead 11 to the diameter of the beads 16. This is done, as will be obvious, without the necessity for any seams or folds or any special operation. The terminal 17 is then clamped over the bead 16 and the attenuated braided conductor to form electrical contact therewith.

It will be understood that my invention is applicable not only in the simple form shown in Fig. 1 but in other and more complex forms. For example, in Fig. 2, I have shown a three conductor co-axial cable. The inner conductor 18 and the intermediate conductor 11 may be substantially as described in Fig. 1 and may be separated by similar insulating beads, or if desired any other interior structure may be used. Over this relatively large central member are strung beads 11a similar to the beads 11 but of larger size and having larger openings substantially fitted to the outside diameter of the intermediate conductor 15 and over these, in a manner similar to that already described in connection with Fig. 1, is fitted the open mesh braided sheath 15a.

I claim:

1. A flexible coaxial cable for low-loss transmission of electrical signals, which comprises a flexible center conductor, a flexible tubular outer conductor substantially coaxial with and spaced from the center conductor, and a plurality of thimble-shaped beads of insulating material strung on the center conductor, each of said beads comprising a hollow cylindrical portion in contact with and providing a supporting surface for the outer conductor and a likewise hollow substantially hemispherical head portion provided with a small hole for centering the inner conductor, the wall of the bead being of substantially uniform thickness throughout and so comparatively thin that the parts of the beads which center the inner conductor do not contact said conductor for more than 25 per cent of the length thereof, that a narrow zone of bearing contact between successive beads is insured and that as large a portion of the space as practicable between the inner and outer conductors is filled with air, while at the same time provision is made for substantially continuous support of the outer conductor in substantially continuously concentric relation to the inner conductor.

2. A flexible coaxial cable according to claim 1 in which the open end of the cylindrical portion of the bead is formed as a right section of the cylinder whereby a sharp bearing edge for engaging the spherical head of the adjacent bead is provided.

3. A flexible coaxial cable for low-loss transmission of electrical signals, which comprises a flexible center conductor, a flexible tubular outer conductor substantially coaxial with and spaced from the center conductor, and a plurality of thimble-shaped beads of insulating material strung on the center conductor, each of said beads comprising a hollow cylindrical portion in contact with and providing a supporting surface for the outer conductor and a substantially hemispherical head portion provided with a small hole for centering the inner conductor, the wall of the bead being so comparatively thin that the parts of the beads which center the inner conductor do not contact said conductor for more than 25 percent of the length thereof, that a narrow zone of bearing contact between successive beads is insured and that as large a portion of the space as practicable between the inner and outer conductors is filled with air, while at the same time provision is made for substantially continuous support of the outer conductor in substantially continuously concentric relation to the inner conductor.

ADRIANO CAVALIERI DUCATI.
